METHOD AND MEANS OF PULLING PIPE
FROM A WELL

Cecil R. Owens, Long Beach, Calif.

Application July 21, 1951, Serial No. 237,874

6 Claims. (Cl. 166—1)

1 In removing pipe or casing from an oil well after the well has stopped producing, or for other reasons, the pipe or casing is gripped by a member and a pull is then exerted on the pipe sufficient to lift it from the well. Due to irregularities in the well, or projections in rock formations, etc., the pipe becomes stuck after a certain length has been pulled from the well and, consequently, the entire string of pipe can seldom, if ever, be removed from the well.

An object of my invention is to provide a method and means whereby a pull can be exerted on the pipe and this pull can then be suddenly released causing a downward jar or jerk on the pipe of considerable intensity, thus loosening the pipe and permitting a greater quantity thereof to be removed from the well.

Another object of my invention is to provide a novel method and means of removing pipe from an oil well in which an upward push or pull is exerted on the pipe of an intensity of less than that which will cause the pipe to part, and then suddenly relinquishing the pull or push on the pipe and permitting the pipe to drop downwardly, thus causing a downward jar which will release the pipe from its attachment in the formation and then by a subsequent upward pull a greater quantity of the pipe or casing can be removed from the well.

Still another object of my invention is to provide a novel means of removing pipe from a well, which consists in exerting an upward force on a collar which is attached to the pipe which is being removed through a medium of shearable pins and causing these pins to shear under a known stress.

Still another object of my invention is to provide a novel method and means of pulling pipe from a well which is effective in operation and which will materially increase the amount of pipe which is recoverable from a well.

Other objects, advantages and features of invention may appear from the accompanying drawing, the subjoined detailed description and the appended claims.

In the drawing:

Figure 1 is a side elevation of my apparatus used in removing pipe from a well.

Figure 2 is a fragmentary longitudinal sectional view of the pulling collar attachment.

Figure 3 is a view similar to Figure 2 showing the pins as having been sheared.

Figure 4 is a sectional view taken on line 4—4 of Figure 2.

Referring more particularly to the drawing,

the numeral 1 indicates the floor of the derrick or the surface of the ground, and the numeral 2 indicates the casing or pipe which extends downwardly into the well and in the case of an oil well this casing or pipe extends downwardly for many thousands of feet. Since pipe or casing is now difficult to obtain it is very desirable to remove as much of this pipe or casing from the well as possible and each additional thousand feet of removed pipe has a distinct value.

The casing 2 is normally at the surface of the ground 1 or at the floor of the derrick and, therefore, can be grasped and pulled upwardly, all of which is usual and well known in the art.

15 My method includes the use of a collar 3 which threads on to the top of the pipe or casing 2, as shown at 4. A plurality of horizontal bores 5 are drilled through the collar 3 and as here shown there are four such bores. A sleeve 6 surrounds the collar 3 substantially as shown. The sleeve 6 is preferably formed with a close fit over the collar 3 so that the shearing action between the sleeve and the collar on the pins will be more effective and as will be subsequently described.

20 The sleeve 6 is provided with horizontal bores 7 which align with the bores 5 and permit the shear pins 8 to be driven into the bores 5 and 7, thus holding the collar 3 and the sleeve 6 in a coupled arrangement as shown in Figure 2. A short length of tubing 9 is threaded or otherwise attached to the bottom of the sleeve 6. The tube 9 is spaced from the pipe or casing 2 substantially as shown. A spider or ring 10 surrounds the tube 9 and shoulders against the bottom of the sleeve 6.

25 The spider 10 may include slips, if desired, for the purpose of gripping the tube 9 or the lower end of the sleeve 6. A pair of arms 11—12 project horizontally from the spider 10, and a hydraulic jack or similar lifting device 13—14 engages the arms 11—12, respectively, thus exerting an upward force against the arms 11—12, the spider 10, and the sleeve 6.

30 When the pipe 2 is stuck in the well and after upward pull will fail to move it, the parts are assembled, as shown in Figure 1, that is, the collar 3 is attached to the top of the casing, the sleeve 6 is placed around the collar, and the shear pins 8 are driven in place, as shown. The hydraulic jacks 13 and 14 will now exert an upward force until the pins 8 will shear. This sudden removal of the upward pull on the casing 2, will cause the casing to drop downwardly into the well very suddenly thus tending to loosen 35 the casing from whatever projection or formation

is hindering its upward movement. Thereafter the casing 2 is then grasped and pulled from the well in the usual manner.

At times it might be possible that the casing 2 would drop downwardly into the well when the pins are sheared and, therefore, a means is provided to catch the casing and prevent it from falling downward great distances into the well. This includes a short length of pipe 15, which screws into the upper end of the collar 3. A coupling 16 may be provided at the upper end of the pipe 15, and an elevator 17 encircles the pipe 15, this elevator being supported from the travelling block 18 by usual links 19. The pipe 15 can push upwardly through the elevator 17 and still if the casing 2 tends to drop downwardly to a greater extent than is necessary this casing would be caught by the coupling 16 engaging the elevator 17.

Having described my invention, I claim:

1. The method of removing stuck pipe from a well consisting of first connecting a sleeve to the pipe by means of shear pins, then pulling upwardly on the sleeve to impart an upward strain on the pipe sufficient to shear said pins, thus suddenly releasing the connection between the sleeve and the pipe to allow the pipe to drop into the well, independently engaging said pipe to permit only a predetermined drop thereof into the well, and then removing the pipe from the well.

2. A means to remove pipe from a well, comprising a collar fixedly mounted on the top of the pipe, a sleeve encircling the collar, shear pins extending through the collar and into the sleeve, means engaging and supporting the sleeve to exert an upward pull thereon, said pins being sheared at a predetermined stress thereon to permit said pipe to retract, and means adapted to engage said pipe to support said pipe independently of said first named means after said pins are sheared and the pipe is retracted.

3. A means to remove pipe from a well, comprising a collar fixedly mounted on the top of the pipe, a sleeve encircling the collar, shearable means connecting the collar and the sleeve, a spider engaging and supporting the sleeve, and hydraulic jacks engaging the spider to exert an upward pull thereon sufficient to release said means connecting the collar and the sleeve, said means being released at a predetermined stress thereon to permit said pipe to retract, and means adapted to engage said pipe to support said pipe

independently of said first named means after the means connecting the collar and the sleeve are sheared and the pipe is retracted.

4. A means to remove pipe from a well, comprising a collar fixedly mounted on the top of the pipe, a sleeve encircling the collar, shearable means connecting the collar and the sleeve, means engageable with the sleeve to exert an upward pull thereon, said shearable means being sheared at a predetermined stress thereon to permit said pipe to retract, and means adapted to engage said pipe to support said pipe independently of said sleeve after said shearable means are sheared and the pipe is retracted.

5. A means to remove pipe from a well, comprising a collar fixedly mounted on the upper end of the pipe, a sleeve fitting over the collar, said sleeve and collar having alignable bores therein, shear pins extending into said bores and connecting said sleeve and collar, said pins being sheared at a predetermined stress thereon to permit said pipe to retract, and means adapted to engage said pipe to support said pipe independently of said sleeve after said pins are sheared and the pipe is retracted, means engageable with the sleeve to exert an upward pull thereon, said pull being sufficient to shear the pins, said means comprising a spider engaging the sleeve, and hydraulic jacks bearing against the spider to press said spider upwardly against the sleeve.

6. The method of removing stuck pipe from a well, which consists in first connecting the pipe and a sleeve surrounding the pipe with a shearable connection, then pulling upwardly on the sleeve to impart an upward strain on the pipe and until the shearable connection is broken to allow the pipe to drop downwardly into the well, independently engaging said pipe in addition to the support of the sleeve to permit only a predetermined drop thereof into the well, and then removing the pipe from the well.

CECIL R. OWENS.
